UNITED STATES PATENT OFFICE.

HARRY L. CURRAN, OF NEW YORK, N. Y., ASSIGNOR OF ONE-HALF TO EDWIN F. KELLOGG AND ONE-HALF TO HENRY L. GILLESPIE, BOTH OF NEW YORK, N. Y.

AMUSEMENT DEVICE FOR EXHIBITING AUTOMOBILES.

1,025,456.

Specification of Letters Patent.

Patented May 7, 1912.

Application filed August 26, 1911. Serial No. 646,271.

To all whom it may concern:

Be it known that I, HARRY L. CURRAN, a citizen of the United States, and resident of New York, in the county and State of New York, have invented certain new and useful Improvements in Amusement Devices for Exhibiting Automobiles, of which the following is a specification.

This invention relates to an amusement device adapted to exhibit automobiles in rapid motion which I term a motordrome.

One of the objects has been to produce such exhibition means in small space and in compact form permitting a full view by spectators and at the same time allowing the automobiles on exhibition to go at high speed.

The novel features of the device will be apparent from the following description taken in connection with the drawings.

In the drawings: Figure 1 is a cross section of a building having my invention applied thereto; and Fig. 2 is a plan view of the device.

As will be seen by reference to Fig. 1 my amusement device may be applied to an ordinary building having a main floor 1 supported in the usual way by posts 2 and the building may be provided with a cover 3 or roof 3 if desired. The main floor 1 is provided with an opening of curved outline and it is preferably made circular as shown. Below the circular opening in the main floor I place a depressed floor 4 which

is considerably below the main floor and which may rest on any suitable supports or on the ground so long as this floor is made firm and sufficiently strong to support automobiles. A track-way 5 extends at an angle

on the edge of the opening in the main floor down to the depressed floor. It is preferably formed by beams 6 extending downward at an angle covered with a board floor, and these beams are braced and supported in any suitable way, the braces 7, 8 and 9 being shown for this purpose. The track-

way 5 has an upper portion extending down to the point 10 which is straight in cross section and which is sufficiently wide to receive automobiles in motion, and in practice I make this portion of the track-way at an angle of about 50° to the horizontal. The joint between this upper portion and the depressed floor is bridged by a lower portion 11 which is placed at a less angle

to the horizontal so that the automobiles may pass from the depressed floor to the upper portion of the track-way without encountering the sharp angle made by the upper portion of the track-way with the depressed floor. This bottom portion 11 is made like the upper portion of the track-way and the track-way, as well as the depressed floor, is made of boards of equal thickness so as to make a smooth surface and they are preferably laid diagonal. Around the upper margin of the track-way I place a guard 12 which may be in the form of a 12 inch board and which serves to prevent the automobile from accidentally running off the track.

The spectators will occupy seats 13 on a raised inclined platform on the main floor around the track as shown and a railing 14 will surround the opening in the main floor so as to prevent spectators from accidentally getting in the exhibition space. In order to admit the automobiles to the track and to the depressed floor I make use of a portable run-way 15 which extends over the edge of the circular opening in the main floor down to the depressed floor 4 at such an angle that automobiles may pass up and down it. In practice I have made the circular opening in the main floor 84 feet in diameter and the inclined track-way at the bottom is 64 feet in diameter, but it will, of course, be understood that the invention is not limited to this exact size.

By the above described construction an automobile on the floor 4 may acquire considerable speed in circling around the floor and it will then pass up onto the upper portion of the track-way 5 and, owing to its inclination and construction, the machine may go at very high speed notwithstanding the very limited space in which it is moving and it is at all times in full view of the spectators.

Having thus described my invention what I claim as new is:

1. In a device of the class described, the combination with a smooth level floor, of a circular track at an angle of about 50° to said floor adapted to receive and support running automobiles, and a narrow intermediate track bridging the joint between said floor and circular track, the said intermediate track being at a less angle to the floor.

2. In a device of the class described, the

combination with a smooth level floor, of a circular track at an angle of about 50° to said floor adapted to receive and support running automobiles, a narrow intermediate track bridging the joint between said floor and circular track, the said intermediate track being at a less angle to the floor, and a continuous guard projecting from said circular track around its upper edge.

10 3. In a device of the class described, the combination with a smooth level floor, of a circular track at an angle of about 50° to said floor adapted to receive and support running automobiles, a narrow intermediate track bridging the joint between said floor and circular track, the said intermediate track being at a less angle to the floor, a continuous guard projecting from said circular track around its upper edge, and removable 15 means for conveying automobiles into said device on said floor.

4. An amusement device of the class indicated comprising a main floor having an opening therein curved in outline, a depressed floor below the opening in the main floor, and an inclined curved track adapted 25 to receive and support running automobiles connecting said floors.

5. An amusement device of the class indicated comprising a main floor having an opening therein curved in outline, a de- 30

pressed floor below the opening in the main floor, a curved track for automobiles connecting said floors at the margin of said opening, said track being inclined and the upper portion being at substantially an angle of 50° to the horizontal, a guard along the top edge of said track, and supports and braces for said main floor and track.

35 6. An amusement device of the class indicated comprising a main floor having an opening therein curved in outline, a depressed floor below the opening in the main floor, a curved track for automobiles connecting said floors at the margin of said opening inclined to the horizontal, the upper portion of said track being straight in cross section for a sufficient distance to accommodate an automobile and the lower portion being at a less angle to the horizontal and bridging the joint between said upper portion and said depressed floor, a guard around the upper edge of said track, and supports and braces for said main floor and track.

40 45 50 55 In testimony whereof I affix my signature in presence of two witnesses.

HARRY L. CURRAN.
